UNITED STATES PATENT OFFICE.

ABRAHAM DANZIGER, OF NEW YORK, N. Y.

AUXILIARY SHEET GAUGE FOR PLATEN PRESSES.

1,423,835.

Specification of Letters Patent. Patented July 25, 1922.

Application filed November 19, 1921. Serial No. 516,430.

To all whom it may concern:

Be it known that I, ABRAHAM DANZIGER, a citizen of the United States of America, residing at the city of New York, in the 5 State of New York, have invented certain new and useful Improvements in Auxiliary Sheet Gauges for Platen Presses, of which the following is a full, clear, and exact description, reference being had to the accompanying drawing, forming part of this 10 specification.

My present invention relates to improvements in platen presses and more particularly to the class having automatic sheet 15 feeding and delivering attachments, it is obvious though that my invention is applicable to other forms of presses than those above mentioned.

One object of the invention is to provide 20 a suitable auxiliary sheet gauge having novel and improved features and of such construction as to be readily applicable to the sheet gauges used in standard construction.

Another object of the invention is to provide 25 a suitable auxiliary sheet gauge having novel and improved features and of such construction as to considerably reduce the cost of labor in the production of printed 30 sheets of various kinds as will be more fully described hereinafter.

It will be understood by those skilled in the art that in platen presses equipped with self feeding devices, the sheets are automatically lifted one at a time from a delivery or 35 feeding platform, passed through the press, receiving the impression of the type, and then deposited on a receiving platform. It will be further understood by those skilled 40 in the art that the delivery platform or that portion of the press on which the sheets are piled in packs ready for feeding, is equipped with adjustable side and end gauges to properly align the pack of sheets relative to the 45 "form;" to the above mentioned side and end gauges my invention is particularly applicable.

To these and other ends, the invention 50 consists in certain improvements and the combinations and arrangement of parts, all as will be more fully hereinafter described, the features of novelty being pointed out particularly in the claims at the end of the specification.

55 In the drawings:

Figure 1 is a longitudinal front elevation

of the delivery or feeding platform with my invention in place thereon.

Figure 2 is a top plan view of a portion of said platform shown in Figure 1. 60

Figure 3 is a detail perspective view of one form of my invention on a larger scale than shown in Figures 1 and 2.

Figure 4 is a detail perspective view of another form of my invention on a larger 65 scale than shown in Figures 1 and 2.

Figure 5 is a top plan view of two superposed bill sheets of different lengths with the same printed heading.

In the present instance 10 designates the 70 delivery or feeding platform, 11, 12 and 13 the walls thereof, 14, 15, and 16 the gauges; the gauges 14 and 15 being adjustable longitudinally on the rod 17 to which they are secured by set screws 18, the major 75 portion of said gauges projecting above the platform 10 through openings or slots 19 and 20; the gauge 16 is adjustable transversely of the platform and is splined in the groove 21 and secured by the set screw 80 22. The slots 19 and 20 extend to approximately only one third of the length of the platform 10 respectively, or to a point indicated by characters 23, 24; the groove 21 extends to a point indicated by 25; to extend 85 the slots or groove further would be to weaken the structure, therefore the movement of the gauges 14, 15, 16 is limited to the length of their respective slots or groove. The parts so far described are standard 90 structure.

To permit of sheets being printed that are smaller in area than the capacity of said gauges, I have constructed the aforesaid auxiliary gauge, as shown in detail in Figures 3 and 4 to be used in conjunction with the gauges 14, 15, 16 at will, according to 95 the requirements. Referring to Figure 3, 26 designates the auxiliary gauge proper, having a rectangular body portion 27, a 100 flange portion 28, a sleeve portion 29 attached to the body portion 27 in any suitable manner and having an extension 30 with an offset downwardly disposed engaging portion 31. In Figure 4, designated by 26^A I 105 have shown the form adapted to be used in conjunction with the gauge 16. The sleeve portions 29, Figures 3 and 4 are adapted to fit over the gauges 14, 15, 16 respectively, to securely hold the auxiliary gauge 26, 26^A 110 in effective relation therewith, the flange portion 28 is adapted to underlie the sheets

32 to prevent said sheets from working under the body portion 27, the engaging portion 31 is adapted to fit in either the slot 19 or 20 to prevent any lateral movement of the body portion 27 and to insure the same properly abutting the sheets 32, Figures 1 and 2.

To further describe the utility of my invention and to demonstrate the reduction in the cost of labor in the production of printed matter, I refer to Figure 5, 33 designates a full sized bill sheet, 34 a smaller or half size sheet, 35 the heading. For sake of illustration, I will say, I wish to print headings 35 on a quantity of full sized bill sheets 33, and the same quantity of half size sheets 34 both to have the same heading 35, I have "made ready" to accommodate the full sized sheet 33 and completed the desired quantity, 20 I now desire to print the half size sheets 34, I discover that I cannot move the gauge 15 over far enough for it to abut the smaller bill sheets 34 due to it being at the end of the slot 20, I must therefore necessarily remove 25 the form from the press and "make ready" again and set the gauges 14 and 15 to accommodate the smaller sheet, with consequent loss of time in making the change.

With my present invention I can avoid this loss of time by simply attaching the auxiliary gauge 26 to the gauge 15 and moving the combined gauges 15, 26 until the body portion 27 abuts the smaller sheet 34, the gauges 14 and 16 remaining in the same position as in printing the full sized sheet 33, I therefore have perfect alignment, without any loss of time. The auxiliary gauge 26 may be used as shown in Figures 1 and 2 in the same manner as described above.

40 The above described auxiliary sheet gauge may be constructed of any suitable material, preferably of metal and of such height as to suit the requirements.

Variations may be resorted to within the scope of the invention and portions of the improvements may be used without the others.

Having thus described my invention, I claim:

50 1. An auxiliary gauge of the character specified, adapted to rest on a sheet delivering platform of a printing press equipped with sheet positioning gauges, with said auxiliary gauge comprising a body portion, and means associated with said body portion to hold said body portion in effective relation with any one of said gauges and said platform.

2. In a platen press having a sheet delivering platform, gauges on said platform adapted to engage the sheets, said gauges being movable within certain limits on said platform, and means whereby sheets of smaller area than the area within the limits

of said gauges may be held in position by 65 said gauges.

3. In a platen press having a sheet delivering platform, gauges on said platform adapted to engage the sheets, said gauges being movable within certain limits on said 70 platform, and means whereby sheets of smaller area than the area within the limits of said gauges may be held in position by said gauges, said means comprising a member attached to any of said gauges, adapted 75 to fill the space between said smaller sheets and the respective gauges.

4. In a platen press having a sheet delivering platform equipped with sheet positioning gauges, the combination of an auxiliary 80 gauge comprising a body portion adapted to abut the sheets on said platform and means associated with said body portion to hold the same in effective relation with any one of said gauges and said platform.

5. In a platen press having a sheet delivering platform equipped with sheet positioning gauges, the combination of an auxiliary gauge comprising a body portion adapted to abut the sheets on said platform, means associated with said body portion to prevent sheets from working under said body portion, and means on said body portion adapted to hold the same and its associated parts in effective relation with any one of said gauges 95 on said platform.

6. In a platen press having a sheet delivering platform equipped with sheet positioning gauges, the combination of an auxiliary gauge comprising a body portion adapted to 100 rest on said platform and abut the sheets thereupon, of a sleeve portion on said body portion, said sleeve portion having an extension with a slot engaging portion, said platform having a guide-slot on which said 105 slot-engaging portion operates, said sleeve portion adapted to hold the body portion and its associated parts in effective relation with any one of said gauges on said platform.

7. In a platen press having a sheet delivering platform equipped with sheet positioning gauges, the combination of an auxiliary gauge comprising an upstanding body portion adapted to rest on said platform and to abut the sheets thereupon, of a flange portion 115 extending from said body and adapted to underlie the sheets, a sleeve portion having a slot engaging portion, said platform having a guide-slot in which said slot-engaging portion operates, said sleeve portion 120 adapted to hold the body portion and its associated parts in effective relation with any one of said gauges on said platform.

Signed at New York in the county of New York and State of New York this 17th 125 day of November A. D. 1921.

ABRAHAM DANZIGER.
